UNITED STATES PATENT OFFICE.

THEODORE C. HOOK, OF PHILADELPHIA, PENNSYLVANIA.

MECHANISM FOR TURNING THE EDGES OF SHEET MATERIAL.

No. 878,631.

Specification of Letters Patent.

Patented Feb. 11, 1908.

Application filed April 12, 1905. Serial No. 255,099.

To all whom it may concern:

Be it known that I, THEODORE C. HOOK, a citizen of the United States, residing at Philadelphia, in the county of Philadelphia and State of Pennsylvania, have invented certain new and useful Improvements in Mechanism for Turning the Edges of Sheet Material, of which the following is a specification.

My invention relates to mechanism for turning the edges of sheet material, such as the edges of covers for paper boxes and the like.

The actions of the devices which effect the folding operations are designed to be as closely analogous as possible to those of the human hand in performing like operations.

The leading objects are to provide mechanism of simple construction and action which will perform its functions rapidly, positively and efficiently.

The characteristic features of the invention will fully appear by reference to the following description and the accompanying drawings in illustration thereof, of which—

Figure 1 is a side elevation of the mechanism shown in its initial position; and Fig. 2 is an enlarged side elevation of a portion of the mechanism showing a box having a cover pressed thereon by a holding device and the extension or edge of the cover held by a turning device in the position to which it has been folded.

The box A which is to be covered is held upon the form B by which it is manipulated. The cover C has the sides c which are to be held against the sides of the box and the side extensions c' which are to be turned over the edges against the inner surfaces of the sides of the box.

The brackets D are part of the frame work of the machine, which may be of any suitable design, it being understood that the mechanism shown constitutes only so much of a box covering machine as is necessary to illustrate the improvements.

The blocks E, each having a projection e, are designed to hold the sides of the cover against the sides of the box. These blocks are fixed on the inner ends of the respective rods F, which are movable longitudinally in the bearings d of the brackets, the rods reciprocating to press the blocks against and withdraw them from the box and cover on the form.

The tumblers G, each having the fingers

g and g', are designed to turn the cover edges or side extensions over the box edges against the surfaces of the box sides. The tumblers are pivotally connected by the pins h to the inner ends of the respective rods H, which are movable longitudinally in the bearings d' in the brackets, the rods reciprocating to move the tumblers into and out of engagement with the edges of the cover and box on the form.

Links or yokes I are fixed to the respective rods H and are provided with the bearings i movable on the rods F. These rods each have the stops f and f' on either side of the corresponding link and a coiled spring J is placed on each rod between the link and the stop f'. These springs act upon the links to move them against the stops f, thereby drawing back the rods H and tumblers G to the position shown in Fig. 1. The springs are compressible to permit these rods to move inward and turn the tumblers to the position shown in Fig. 2 after the blocks E have reached the limit of their inward movement, in contact with the sides of the box and cover on the form.

It will now be understood that when a box with its cover are held by the form between the presser blocks, as shown in Fig. 1, and the tumbler rods are thrust inwardly, these rods will act through the links upon the springs to thrust the presser block rods inwardly so that the blocks press the sides of the cover against the sides of the box. The blocks having thus reached the limit of their inward movement, the tumbler rods continue to move inwardly against the action of the springs upon the links, and the tumblers are carried to the position shown in Fig. 2, the lower finger of each tumbler engaging the projection on the corresponding presser block and the block being thereby turned so that the upper finger folds the edge of the cover over the edge of the box. The edges having been folded, the tumbler rods are drawn back to disengage the tumblers, and in sequence therewith the presser blocks, the springs acting to hold the presser blocks in engagement with the box and cover until the tumblers have been disengaged therefrom. Two side extensions of the cover being thus folded, the other two extensions may be folded by turning the box, by mechanism duplicating that shown, or otherwise adding to this mechanism.

Having described my invention, I claim:—

1. In apparatus of the class described, a form, a plurality of independently movable oppositely reciprocating holding devices adapted to press material against the same, and a plurality of turning devices one for each holding device and reciprocating in paths parallel to the paths of reciprocation of the respective holding devices and having 5 limited movements of reciprocation independent of the movements of said holding devices respectively, each turning device being constructed to engage and be turned by its respective holding device.
- 15 2. In apparatus of the class described, a form, a reciprocating rod, a presser block on said rod, a second reciprocating rod, mechanism comprising a spring for connecting said rods, and a turning block pivoted on 20 said second rod, said turning block being

operated through contact with said presser block.

3. In apparatus of the class described, a bearing, a rod reciprocating in said bearing and having a device for holding material to be folded, a second bearing, a rod reciprocating in said second bearing, flexible mechanism for connecting said rods whereby one has a limited motion with reference to the other, and a device pivoted on said second rod and 25 tilted by engaging a part with relation to which it moves to fold an edge of the material held by said first device.

In testimony whereof, I have hereunto affixed my signature in the presence of two 30 subscribing witnesses.

THEODORE C. HOOK.
